ROTARY SPRINKLER

Louis Meinholt, Hamilton, N. Y.

Application April 6, 1931. Serial No. 528,184

4 Claims. (Cl. 299—69)

This invention relates to rotary sprinklers, and especially to a sprinkler of the type known, in the manufacture of vinegar, as a sparger.

In order that the purpose of the invention may be fully understood, it is explained that in the manufacture of vinegar, a tall vat or receptacle is filled with corn-cobs, rattan shavings, etc., to provide large surface area over which is sprinkled a liquid such as hard cider, so the alcohol in the liquid may be readily converted into acetic acid. The purpose of the sparger is to distribute the liquid evenly over the material in the vat or receptacle.

One object of this invention is to provide a very simple form of rotary sprinkler or sparger which consists of comparatively few and simple parts, so it can be manufactured at a comparatively low cost.

Another object is to provide an improved sparger which has a self-regulating feature to prevent excessive speed of rotation, at the same time preventing waste of the liquid being sprinkled or distributed.

Another object is to provide an improved sparger of materials which are proof against corrosion and other detrimental effects of the acid in the cider and of the fumes from the acetic acid.

Other objects and important features are pointed out or implied in the following details of description in connection with the accompanying drawing in which:

Fig. 1 is a top plan view of my improved sparger. Fig. 2 is a view partly in side elevation, and partly in central vertical section.

Referring to the drawing in detail, in which similar reference characters correspond with similar parts in the several views, the invention is described in detail as follows:

40 A funnel-like receptacle 5 has its lower end internally threaded at 6, and within this threaded aperture is fitted the screw-threaded lower end portion of a vertical tube 7 which has a vertical slot 7a in its intermediate part, the lower end of this slot terminating at the bottom of the receptacle 5. The upper end of the tubular member 7 has a plug 8 secured therein, by solder or other appropriate means 9, and this plug 8 is centrally apertured to provide a bearing of a pivot-rod 10. 45 The upper end of this pivot-rod is secured in an apertured wall of a feed-pipe 11 through which the cider passes from a tilting receptacle or other intermittent feeding device (not shown). Solder or welding material 12 may be employed for sealing the pivot-rod 12 in a fixed position. It has

a bent intermediate part, so that its lower end is vertical and axially aligned with the feed-pipe 11 and the tube 7.

A lock-nut 13 is threaded on the tube 7, and bears against the lower end of the receptacle 5, for holding it in fixed relation to the tube 7.

A special form of T-pipe or hollow connection 14 is threaded on the lower end of the tube 7, and has an apertured boss 15 in which is secured a pointed pivot 16. A pivot-bearing 17, preferably of glass, is secured to a supporting bar 18 which may have its ends resting on opposite sides of the vat or container of the material to be sprinkled.

The T-pipe or connection 14 has laterally apertured sprinkler-tubes 19 screwed therein, and the ends of these tubes are plugged as indicated at 20. The apertures 21 of one of the tubes 19 are on opposite sides from that of the similar apertures of the other tube. Therefore, the liquid will flow in opposite directions, and such flow will cause the sparger to rotate while the liquid is flowing, by the reacting force which is well understood by those who are familiar with the art. 75 The purpose of spacing the apertures 21 nearer and nearer together from the inner to the outer ends of the tubes 19, is also well understood by persons familiar with the art, as obtaining the most even distribution of the liquid.

The upper and intermediate parts of the tube 7 have two important functions, that is, as a pivot-bearing at 8—10, and as a regulating feature at 7a, in connection with the upwardly inclined wall of the receptacle 5. In this latter 80 connection, assume that the receptacle is nearly full of cider, that the cider is flowing through the slot 7a, thence through the lower part of the tube 7, into the parts 14 and 19, and out through the apertures or jet-openings 21, and that the sparger begins to rapidly rotate to such an extent that the sprinkling would be excessive at the outer part of the material being sprinkled, while no sprinkling would be done at the central part, because of the centrifugal force. This centrifugal force also tends to throw the cider against the inclined wall of the receptacle 5, and by such action to raise the liquid in the receptacle, so as to reduce the pressure at the slot 7a, and thereby 85 reduce the force which tends to turn the sparger. As the speed of revolution is reduced, the cider resumes its normal pressure at the slot 7a; so the speed will tend to maintain a predetermined normal which may be governed by the depth of the 90 funnel-like receptacle 5, by the capacity of the 95 feed-pipe 11, or by the rate of flow of the liquid. 100

slot 7a, and by other relative dimensions of the device and of the apertures thereof.

The tubes and T-connection as well as the parts 5, 8 and 13, may be of hard rubber or other non-metallic and non-corrosive materials; and inasmuch as these can not be very tightly screwed together, because of the danger of breaking them, it is desirable that a practical and effective supporting and locking means be provided, and therefore, rods 22 and 23 preferably of stainless steel or other non-corrosive material, are formed and connected as shown; that is, the upper ends of the rods 22 extend through openings 24 and are bent to secure them against outward movement. The lower ends of these rods are curved around the lower sides of the tubes 19 and secured thereto as indicated at 25, so as to support the outer ends of these rods, and at the same time prevent them from becoming unscrewed by accident. The intermediate parts of the rods 22 are formed with loops 26, which are engaged with loops 27 of the rods 23. These latter rods have their lower ends secured to the tubes 19 in the same manner explained with regard to the rods 22.

Although I have described this form of my invention specifically, I have no intention of limiting my patent protection to these exact details of construction, arrangement, or materials, for the invention is susceptible of numerous changes within the scope of the inventive ideas as implied and claimed.

What I claim as my invention is:

1. In a rotary sprinkler, the combination of a funnel-like receptacle, a vertical tube longitudinally centered in the axis of rotation and provided with a vertical pivotal connection at its upper end, said tube extending through and closing the lower convergent end of said funnel-like receptacle and united therewith and having an opening at a point above and near the bottom of said receptacle for permitting liquid to pass from the receptacle to the interior of said tube, a hollow connection united with the lower end of said vertical tube and in open communication therewith and provided with a vertical pivot, and sprinkler-tubes united with the hollow connection and in open communication therewith and extending horizontally in opposite directions, each of said sprinkler tubes having its outer end closed and having a series of jet-openings along one of its sides, the jet-openings of one sprinkler-tube being on the opposite side from those of the other sprinkler-tube, substantially as shown, for the purposes specified.

2. The structure defined by claim 1, a liquid-supply pipe having an outlet in its lower end and directly over the upper pivotal connection of said vertical tube, the latter having its upper end closed by the upper pivotal connection, the said upper pivotal connection including a pivot-rod united with the wall of said liquid-supply pipe, whereby the latter performs the dual function of supplying liquid to the sprinkler and helping to support the sprinkler.

3. In a rotary sprinkler, the combination of a funnel-like receptacle, a vertical tube having a pivotal connection at its top, said tube extending substantially from the top to and through the bottom of the funnel-like receptacle and closing said bottom and having an opening at said bottom to permit liquid to pass from the receptacle to the interior of said vertical tube, a hollow connection on the lower end of said vertical tube and having a pivotal connection on its under side, sprinkler-tubes screwed into said hollow connection and extending horizontally and having jet-openings positioned for causing rotation of the sprinkler about said pivotal connections, and rods each connected to said receptacle and to one of said sprinkler-tubes in proper relation for supporting the ends of the sprinkler tubes and preventing the sprinkler-tubes from accidentally unscrewing.

4. In a rotary sprinkler, the combination of a funnel-like receptacle for liquid, said receptacle having an inverted-conical wall, a vertical tube extending through the receptacle in concentric relation to the axis of rotation, said receptacle and tube being intimately united in such relation that the wall of the receptacle is imperforate at its bottom, means independent of said tube for supplying liquid to said receptacle in the space around said tube, a hollow connection secured to the lower end of said tube under said bottom and in open communication with said tube, sprinkler tubes united with said hollow connection and in open communication therewith and extending oppositely therefrom, said sprinkler tubes having outlet openings in proper relative positions for imparting rotary motion to said sprinkler about said axis, pivotal connections aligned with said axis at the upper and lower ends of the sprinkler, the said vertical tube having a lateral vertical slot through which its interior communicates with the space therearound in said receptacle, whereby more fluid may flow through the device if there is a tendency of the device to slow down in its rotation.
